UNITED STATES PATENT OFFICE

MONA MORGAN, OF NEW YORK, N. Y.

SHAMPOO SHIELD

Application filed July 5, 1928. Serial No. 290,596.

My invention aims to provide an exceptionally simple and a rather inexpensive device for individual use by persons who shampoo their own hair, the device being constructed to prevent soapy water or other liquid which may be used on the hair, from running down the forehead and the sides of the face and into the eyes.

With the foregoing in view, the invention resides in the novel subject matter hereinafter described and claimed, the description being supplemented by the accompanying drawing.

Figure 1 is a side elevation showing the device applied.

Figure 2 is a perspective view of the shield.

Figure 3 is an enlarged detail transverse sectional view showing the device applied and illustrating more particularly the manner in which it snugly engages the user's head.

In constructing the device, I make use of a resilient frame which is preferably formed from a single length of wire. This frame comprises a horizontally curved upper portion 1 which is adapted to extend around the user's forehead, and from the ends of this curved portion, two arm portions 2 extend downwardly for disposition at the sides of the face, in front of the ears. Preferably, the lower ends of the arm portions 2 are extended rearwardly to provide finger portions 3 which are intended to underlie the ears and extend along the sides of the neck.

The rear ends of these finger portions are preferably formed with eyes 4 adapted to be connected by a strip of elastic 5 or some other flexible tie, intended to pass around the back of the user's neck.

The frame carries a trough-like water conductor which conductor preferably comprises a rubber tube 6 around the portions 1, 2 and 3 of said frame, and inner and outer, flexible, rubber flanges 7 and 8 integral with and diverging from the tube. The inner flange 7 is intended to yieldably engage the forehead, the sides of the face and the sides of the neck, thus preventing any liquid from creeping downwardly or forwardly, while the hair is being shampooed, and obviously,

the flange 8 catches any water or the like running down the flange 7, so as to direct it downwardly and rearwardly. Thus, the device absolutely prevents any soapy water or other liquid used in shampooing, from running over the face, and into the eyes or mouth.

The device is exceptionally simple and inexpensive, yet is very desirable, as it may be quickly and easily attached or detached, and will effectually perform the function for which it is designed. As excellent results are obtainable from the details disclosed, they may well be followed. However, within the scope of the invention as claimed, modifications may of course be made.

Due to the form-retaining characteristic of the frame, there is no difficulty encountered in properly applying the device each time it is to be used, and the necessity of adjusting various portions to their proper positions and fastening them as in prior contrivances, is overcome.

I claim:

1. A shampoo shield comprising an elongated one-piece resilient form-retaining member having its central portion longitudinally curved to fit the user's forehead from temple to temple, said member being bent to provide face-gripping portions extending downwardly from the ends of said curved portion, said member being provided with relatively long and narrow water-conducting means whose length follows the length of said member from end to end, said water-conducting means being carried solely by said member.

2. A shampoo shield comprising a single wire whose central portion is longitudinally curved to fit the user's forehead from temple to temple, said wire being bent downwardly from the ends of said curved portion to provide two face-gripping arms, the extremities of said wire being free and bent rearwardly to underlie the user's ears, and a relatively long and narrow water conductor whose length follows the length of said wire, said conductor being carried solely by said wire.

3. A shampoo shield comprising a single wire whose central portion is longitudinally

curved to fit the user's forehead from temple to temple, said wire being bent downwardly from the ends of said curved portion to provide two face-gripping arms, the extremities of said wire being free and bent rearwardly to underlie the user's ears, said rearwardly bent portions being further bent at their rear ends to provide eyes, a flexible tie connected with said eyes to pass behind the neck, and a 10 relatively long and narrow water conductor whose length follows the length of said wire, said conductor being carried solely by said wire.

4. A shampoo shield comprising a single wire whose central portion is longitudinally curved to fit the user's forehead from temple to temple, said wire being bent downwardly from the ends of said curved portion to provide two face-gripping arms, the extremities of said wire being free and bent rearwardly to underlie the user's ears, a flexible tube 20 snugly surrounding said wire from end to end, and inner and outer flexible flanges integral with and extending throughout the 25 length of said tube, said flanges jointly forming a water-conducting trough.

In testimony whereof I have hereunto affixed my signature.

MONA MORGAN.
